UNITED STATES PATENT OFFICE.

JOHN W. SPARKS, OF SABINA, OHIO.

LOCKING-CLOSURE FOR BURIAL-VAULTS.

No. 892,909.

Specification of Letters Patent.

Patented July 7, 1908.

Original application filed June 26, 1907, Serial No. 360,923. Divided and this application filed September 6, 1907.
Serial No. 391,638.

To all whom it may concern:

Be it known that I, JOHN W. SPARKS, a citizen of the United States, residing at Sabina, in the county of Clinton and State of Ohio, have invented certain new and useful Improvements in Locking-Closures for Burial Vaults; and I do hereby declare the following to be a full, clear, and exact description of the invention, such as will enable others skilled in the art to which it appertains to make and use the same.

In my application for Patent Serial No. 380,923, filed June 26, 1907, for improvements in mausoleums or burial-vaults, I have illustrated and described, as a cell-closure, an improved door or "lock-plate" with fastening and locking mechanism carried thereby; which subject-matter is made the basis of this application, filed as a division of the above application Serial No. 380,923.

The object of my present invention is to provide an efficient and practicable closure, together with fastening means therefor, for various depositories, receptacles or inclosures, more particularly appropriate however for burial-vaults and other storage cells or depositories.

As a further object, my invention provides means whereby the door or plate constituting the closure may be temporarily fastened, and locked if desired, or may become permanently self-locked so that thereafter the door or closure cannot be removed except by demolishing the structure of the depository; this being especially desirable where the closure is applied to a burial-vault or depository for preserving other objects indefinitely and inaccessibly.

As a further object, my invention provides a closure having means for effecting a hermetical or air-tight and moisture-tight seal, which is obviously advantageous where the contents of the depository need to be guarded against the influence of air and dampness, as for example a dead body.

These and certain minor objects herein-after appearing are accomplished by means substantially as herein described and particularly pointed out in the appended claims; reference being had in the description to the accompanying drawings, hereby made a part of this specification, and wherein:

Figure 1 is a central horizontal section through a portion of a concrete burial-vault, to which my invention is shown applied.

Fig. 2 shows the back face of the door or plate constituting the closure, with the fastening or locking mechanism carried thereby. The lock-bolts carried by the plate or door are shown retracted, while their extended positions are indicated by dotted lines. Fig. 3 is a view similar to Fig. 2 illustrating a modification. Fig. 4 is a front view of the door or lock-plate. Fig. 5 is a perspective view of the door or lock-plate together with an outer plate or tablet which is or may be used in conjunction therewith. Fig. 6 shows in front view a fragment of said outer plate or tablet with the adjacent portions of the depository-walls in section. Fig. 7 is a detail section on line 6—6 of Fig. 6.

Referring to the drawings by specific reference symbols, let A denote the walls of a mausoleum or burial-vault, having therein a cell C to which my improved closure is shown applied.

G denotes a metal door or plate, preferably of thick steel, adapted to fit within the mouth or open end of the cell, and desirably having a flange *g* projecting from its back or inner face. Said plate G, being equipped with locking mechanism, may be appropriately termed a "lock-plate". At the back of said plate is a pivotal or rotary disk H, or equivalent element, rigidly mounted on the inner end of an arbor I, which is journaled in and extends through a central opening in the lock plate. At the front of the lock-plate, rigidly-mounted on the outer end of said arbor, is a crank J, preferably a double crank-bar equipped with short knobs or handles *j*, at opposite sides of the arbor, affording a grip for turning the crank and thereby turning the disk H. The front of the plate G is desirably made with a depression or countersink for the crank-bar, although this is not essential.

At preferably diametrically opposite points on the disk H, are pivotally-attached the inner ends of oppositely-projecting lock-bolts K, which are guided through or under loops *k* on the back of the lock plate. By turning the disk H in reverse directions, by means of the crank-bar J, said lock-bolts K can be moved outward and inward, to engage with or disengage from suitable sockets or catches in the walls of the cells; the turning of the crank J in one direction throwing out the lock-bolts beyond the perimeter of the lock plate, and the reverse movement of the crank

retracting said lock-bolts within the perimeter of the plate. The disk H may have a raised hub h^1 which will engage and hold the inner ends of the lock-bolts when shoved outward to locking position. Instead of two diametrically-located lock-bolts, it would be practicable to employ three or more lock-bolts arranged at different positions on the back of the lock-plate, and adapted to engage in correspondingly-arranged sockets or catches therefor in the cell-walls, though the arrangement shown is preferred.

As shown in Figs. 1 and 2, adjustable set-screws k^1 are tapped through the loops k and swiveled to small plates or washers k^2 , the latter bearing on the lock-bolts K, so as to hold them toward the plate. Or, as shown in Fig. 3, similar set-screws may pass through longitudinal slots in the lock-bolts and be tapped in the lock-plate itself, suitable washers k^3 being interposed between the lock-bolts and the heads of the set-screws. This adjusting feature, while constituting a subsidiary feature of my invention, is not indispensable.

The disk H, which may appropriately be termed a "ratchet-disk", has a segment of its periphery provided with ratchet-teeth h , adapted to be engaged by a spring-pressed pawl L, which is pivotally-mounted on the plate G and normally held in engagement with the teeth of the ratchet-disk H by a spring l, secured at one end to said plate its free end contacting with the upper face of said pawl. The arrangement of the ratchet-teeth h and pawl L is such as to permit turning the ratchet-disk only in a direction to project or force outward the lock-bolts K. However, the pawl can be disengaged and held disengaged from the ratchet-disk, so as to permit turning the latter in either direction; the purpose of which will appear later. Various contrivances may be adopted for this purpose; two suitable arrangements being represented in Figs. 2 and 3 respectively. In Fig. 2, the spring l is shown bearing the pawl L against the ratchet-disk. To set the pawl out of engagement, it is merely necessary to place the spring under the pawl, or between the pawl and ratchet-disk, as indicated by dotted lines; the spring thus doing double duty. In Fig. 3, the spring l is shown as a tail-lever of the pawl L, acting between the pivot of the pawl and a stud l^1 . To disengage the pawl from the ratchet-disk, the spring may be placed under another stud l^2 closer to the ratchet-disk.

Between the disk H and plate G, surrounding the arbor I, it is desirable to interpose a gasket or packing M of rubber, asbestos, or other suitable compressible packing material, placed in opposed concavities in the confronting faces of the disk and plate. The compression of this packing, effected by drawing the disk H against the plate G,

crowds it around the arbor I and thereby makes an air-tight joint, so as to prevent access of air or moisture through the central opening of the plate. For drawing the disk against the lock-plate, oppositely arranged segmental inclines or raised inclined surfaces N are provided on the front of the lock plate, under the respective arms of the crank-bar J, the highest portions of the inclines being under that position which the crank-bar occupies when the lock-bolts are thrown outward. Hence, by turning the crank-bar in a direction to force out the bolts, said crank-bar will ride on the inclined surfaces and thereby draw the disk H against the plate G compressing the aforesaid packing M.

One end of the crank-bar J is provided with an apertured lug or flange j^1 . The front of the plate G is provided with a segmental flange g^1 , located so as to confront the flange j^1 when the crank-bar J is moved to locking position. The hasp of the pad-lock x may then be entered through registering apertures in the flanges j^1 and g^1 , in order to lock the crank-bar in said locked position, for a purpose hereinafter explained.

The above described lock-plate G sets or fits within the mouth or open end of the cell, and may abut against a shoulder or abutment c therein, the back flange g of the plate also fitting within the walls of the cell adjacent said shoulder c. Said shoulder is desirably provided by abruptly enlarging the mouth of the cell, or forming a rabbet around the mouth of the cell. Behind said shoulder c are the recesses or sockets c¹ in the cell-walls for the reception of the outer ends of the lock-bolts K, or in lieu thereof any suitable catches may be provided for engagement by the lock-bolts. The front walls of said sockets c¹ are in this instance shown faced with metal embedded in the cell-walls; the specific metal facings shown consisting of substantial Z-shaped anchors O embedded in the structure in the manner represented in Fig. 1. The present drawings also show the opposing surfaces of the shoulder c and plate G formed with continuous mating or confronting grooves indicated by c² and g² respectively, designed to receive a packing or sealing substance P, as cement, asbestos, rubber or other suitable material; so that when the plate G is shoved back against the shoulder c, the said packing or sealing substance will establish an air-tight connection, which, in addition to the air-tight seal around the arbor I of the plate G, hermetically seals the mouth of the cell. To draw the lock-plate against the shoulder c, the outer ends of the lock-bolts K are desirably offset or inclined backwardly from the plate G, so that as said lock-bolts are forced outward and into the recesses c¹, they will ride against the metallic anchors or catches O, and thereby 130

forcibly draw the plate G inward, compressing the packing or seal P between the plate and shoulder c.

Prior to depositing a casket or such other object as is to be preserved or safe-guarded in one of the cells, the lock-plate G thereof is detached, the spring-pawl L is disengaged from the ratchet-disk H so as to permit the lock-bolts K to be withdrawn from the recesses or catches in the cell-walls by a reverse turning of the crank-bar J. After depositing a body or casket in the cell, the lock-plate is put in position, and may be either temporarily or permanently secured, according to circumstances. If only a temporary closure is desired, the pawl L is still held disengaged from the ratchet-disk H, so as to permit turning the crank J in either direction, for moving the lock-bolts into or out of engagement with the sockets or catches in the cell-walls. When the mechanism of the lock-plate is so adjusted for temporary locking, the crank-bar J may be locked in position by means of a pad-lock, the hasp of which may be inserted through apertures in the flanges j¹ and g¹ as before mentioned, so as to insure against any unauthorized or promiscuous access to the cell. But when it is desired to make a permanent closure, the pawl L is released and allowed to engage the ratchet-disk H, and the lock-plate G is then shoved back into position against its stop or shoulder c, a supply of cement, mortar or the like, or a packing of other suitable substance, being first interposed in the grooves c², g² between the lock-plate and shoulder c. The crank-bar J is then turned to force the lock-bolts K outward and into the recesses or sockets or into engagement with the catches provided in the cell-walls; and, as said lock-bolts move outward, their inclined ends ride against the metallic anchors O; thereby drawing the lock-plate G inward against the shoulder c, and compressing the interposed cement or packing P, while the turning of the crank-bar J on the inclines N also effects compression of the packing M around the arbor I, as before explained, thus hermetically sealing the cell. It is now impossible to withdraw the lock-bolts K by any means whatsoever, and access to the cell cannot be had except by demolishing the structure, which, by reason of its strong concrete formation, is practically secure against depreciation.

A tablet D, as an inscription tablet for a burial-vault, is or may be inserted in the mouth of the cell after the lock-plate G is secured in position, and it may rest against the front of the lock-plate, or, if preferred, there may be an intervening space between the lock-plate and the tablet D which can be filled with cement when the cell is permanently sealed. The tablet D is desirably formed with a groove d around its perimeter,

and the mouth of the cell is formed with a mating groove a. In sealing the cell, said grooves are filled with cement and the tablet D is pushed in place, whereupon the cement in the two grooves will meet and set, forming a secure fastening for the tablet, also making an additional sealing for the cell. It is necessary, of course, to hold the tablet in position until the cement hardens. This may be done by any suitable means. For example, in order to hold the tablet temporarily in place, dowel-pins d¹ may be provided in either the upper or lower edge of the tablet, preferably the upper edge, as shown in Figs. 5 and 6, these pins adapted to enter recesses therefor in the corresponding wall of the mouth of the cell. In putting the tablet in place, the tablet would first be held in position to engage the dowel-pins in the recesses therefor, and then the tablet would be lifted, and at the same time shoved back into position.

Another means of holding the tablet in place, is shown in Figs. 5 and 7, where bolts or threaded rods are entered through loops or hooks r on the outer face of the lock-plate G; said bolts or rods adapted to pass through holes therefor in the tablet and to receive finished washers and nuts r¹ to hold the tablet in place. The nuts r¹ may be made of ornamental designs. This arrangement is especially desirable for the temporary closure. It may also be used for the permanent sealing of the cell, either alone, or in combination with the means already described, the bolts holding the tablets securely while the cement in the mating grooves a and d hardens.

I do not, of course, desire to be limited to any specific means for holding the tablet in place, the means shown herein being illustrated only by way of example; nor is my improvement in the lock-plate and locking mechanism essentially limited to the use therewith of an outer tablet.

Instead of recesses c¹ in the cell-walls for reception of the lock-bolts K, the cell-walls may be provided with suitable projections behind which the lock-bolts will engage, said projections being firmly anchored in the walls. Said projections, with additional ones if necessary, may also take the place of the shoulder or abutment c, in cases where it is desired to make the cell of a uniform cross-sectional area throughout its length. These and other modifications in details are comprehended within the scope of my invention.

I claim as my invention and desire to secure by Letters Patent of the United States:

1. A plate or door adapted as a closure for vault-cells and having, in combination, lock-bolts adapted to engage catches or sockets in the walls of said cells, means for moving said lock-bolts outward and inward, and means for fixing the lock-bolts permanently or non-

- detachably in outward or locked position at will.
2. A plate or door adapted as a closure for vault-cells and equipped with mechanism for engaging and disengaging means in the walls of said cells, said mechanism having means whereby it may be permanently set in locked position without permitting subsequent unlocking thereof.
- 10 3. A plate or door adapted as a closure for vault-cells, locking mechanism carried thereby, actuating means on the front of said plate operatively-connected with said mechanism for locking and unlocking, and means on and accessible only at the back of said plate adapted to be operatively-connected with said mechanism so as to prevent unlocking thereof after said mechanism has been moved to locking position.
- 20 4. A plate or door adapted as a closure for vault-cells and having, in combination, a crank on the front of said plate, a disk on the back of said plate, an arbor journaled in said plate on which said crank and disk are rigidly mounted, lock-bolts for engaging in or with devices in the walls of the depository, the inner ends of said lock-bolts being pivotally-attached to said disk, and means on the back of said plate to prevent reverse turning of said disk after it has been turned in a direction to move outwardly the lock-bolts.
- 30 5. A plate or door adapted as a closure for vault-cells and having, in combination, a crank on the front of said plate, a disk on the back of said plate, an arbor journaled in said plate on which said crank and disk are rigidly mounted, and lock-bolts for engaging in or with devices in the walls of the cell, the inner ends of said lock-bolts being pivotally-attached to said disk, said disk having ratchet-teeth, a spring-pressed pawl on the plate adapted to engage said ratchet-teeth, whereby the disk can be turned only in a direction to force out the lock-bolts, and means for holding said pawl disengaged from said ratchet-teeth to allow moving the lock-bolts in either direction.
- 40 6. A plate or door adapted as a closure for vault-cells and having, in combination, a crank on the front of said plate, a disk on the
- back of said plate, an arbor journaled in said plate on which said crank and disk are rigidly mounted, and lock-bolts for engaging in or with devices in the walls of the cell, the inner ends of said lock-bolts being pivotally-attached to said disk, means for guiding said lock-bolts, and adjusting screws for holding the lock-bolts toward the plate.
7. The combination in a vault-cell, of a plate or door adapted to set therein, a crank on the front of said plate, a disk on the back of said plate, an arbor journaled in said plate on which said crank and disk are rigidly mounted, and lock-bolts for engaging in or with devices in the cell-walls, the inner ends of said lock-bolts being pivotally-attached to said disk, a packing interposed between said disk and plate around said arbor, and an inclined surface on the front of the plate on which said crank will ride when moved to locking position, thereby compressing said packing.
8. The combination in a vault-cell, of a plate or door adapted to set therein, a crank on the front of said plate, a disk on the back of said plate, an arbor journaled in said plate on which said crank and disk are rigidly mounted, and lock-bolts for engaging in or with devices in the cell-walls, the inner ends of said lock-bolts being pivotally-attached to said disk, said crank having an apertured flange or lug, and an apertured flange or lug on the front of said plate which said first-mentioned flange confronts when the crank is turned to locking position, whereby the hasp of a pad-lock can be inserted through said flanges.
9. The combination with the lock-plate, having bolts or threaded rods projecting from its outer face, of the tablet adapted to fit in the mouth of the cell, and having apertures to receive said bolts and nuts or screw caps for engaging said bolts on the outside of the tablet.

In testimony whereof I affix my signature, 95
in presence of two witnesses.
